UNITED STATES PATENT OFFICE.

EDGAR H. MORGAN, OF FREEPORT, ILLINOIS, ASSIGNOR TO ARCADE MANUFACTURING COMPANY, OF FREEPORT, ILLINOIS, A CORPORATION OF ILLINOIS.

DESIGN FOR A BOTTLE-OPENER.

41,124.

Specification for Design.

Patented Jan. 24, 1911.

Application filed November 13, 1909. Serial No. 527,960. Term of patent 14 years.

To all whom it may concern:

Be it known that I, EDGAR H. MORGAN, a citizen of the United States, residing at Freeport, in the county of Stephenson and State of Illinois, have invented a new, original, and ornamental Design for a Bottle-Opener, of which the following is a specification, reference being had to the accompanying drawing, forming part thereof.

The figure is a perspective view of a bottle-opener, showing my new design.

I claim:

The ornamental design for a bottle-opener, as shown.

EDGAR H. MORGAN.
